QUILTING FRAME STAND

Anna D. W. Janssen, Crete, Nebr.

Application February 23, 1937, Serial No. 127,057

2 Claims. (Cl. 45—24)

My invention relates to devices for supporting a quilting frame and for clamping the members of the frame together, the primary object of the invention being the provision of a combined support and clamp for holding the frame in rectangular relation at a convenient height above the floor.

Another of my objects is the provision of a stand or support consisting of four upright posts having clamping devices secured to the posts.

Another object which I have in view is the provision of corner posts, each post having a clamp for engaging the end portion of a side rail of the quilting frame and having also a clamp for engaging the end portion of an end rail of the quilting frame.

Another object is the provision of a support for a quilting frame together with clamping members which cooperate with the support for engaging the quilting frame to clamp the members thereof against the stand.

Still another of my objects is the provision of a corner post support for a quilting frame with devices for tightly clamping the members of the frame against the posts.

Having in view these objects and others which will be pointed out in the following description, I will now refer to the drawing in which

Figure 1 is a view in isometric projection showing the quilting frame secured to the support and having a quilt thereon, the parts being arranged as they appear when in use.

Figure 2 is a view in isometric projection of one of the corner posts with the feet folded against the post.

Figures 3, 4 and 5 are side elevational views of the upper portion of a post and showing particularly the action of the clamping members in various positions of adjustment.

The quilting frame itself is the common and well known frame consisting of a pair of side rails 10 and a pair of end rails 11 arranged in rectangular relation. The rails must be secured together at the corners of the frame and this is usually done by means of a specially designed clamp which has been in use for many years. The frame with the quilt is usually supported on a table, bed, the backs of chairs or anything else that can serve as an improvised support. My invention is designed to provide the support combined with clamping devices which are far superior to the prior clamps.

The support includes four posts 12 having feet 13 for maintaining the posts in upright and stable position. Each post has a pair of apertures

for receiving bolts 14 and 15 respectively, the aperture for the bolt 14 being transverse to the rail 10 and the aperture of the bolt 15 being transverse with respect to the rail 11. The two apertures are spaced apart a distance slightly greater than the combined thickness of the two rails. The bolt 14 is L-shaped for clamping the rail 10 against the post 12 as best shown in Figure 5. Similarly the bolt 15 is adapted to clamp the rail 11 against the post 12 as best shown in Figure 4. The bolt 15 has an inclined and in-turned projection 15' having a definite function during quilting. The bolts 14 and 15 are provided with wing nuts for convenience in tightening and loosening the quilting frame without difficulty or loss of time. The posts 12 are preferably provided with a second pair of apertures 16 spaced vertically from the apertures occupied by the bolts 14 and 15. The quilting may be done from chairs or other seats of various heights so that a second pair of bolt holes makes possible the adjustment of the quilting frame to a convenient height.

The posts 12 are maintained individually in upright position by means of the feet 13 so that the quilting frame is maintained in exceedingly stable position during use. For storage, however, it is desirable that the feet be foldable to conserve space. The feet 13 are therefore hinged at 17 to be folded against the post 12 as shown in Figure 2. Links 18 are pivotally secured to the feet 13 and these links are provided at their free end portions with notches for engaging the pins 19 projecting from the post 12 to latch the feet in their operative position and to thereby prevent the collapse of the support while the work is going on.

The utility of my quilting frame stand will be obvious to those skilled in the art. The frame is set up in the manner shown in Figure 1 and the clamps are drawn tight so that the quilting frame is supported at a convenient height and in rigid rectangular form. The quilt is secured to the end rails 11 in the usual manner, the most common method being by pinning to a layer of fabric surrounding the end rails. If the quilt is too slack, the bolts 14 at one end of the frame are released so that the two posts with the end rail may be slidably shifted outwardly until the quilt is taut after which the bolts 14 are tightened. As the work of quilting progresses from either or both ends of the quilt it becomes necessary that one or both ends of the quilt be rolled to bring the unworked portion of the quilt within convenient reach. This may be done by loosening both bolts 15.

14 and 15 from clamping engagement at the end which is to be rolled whereupon the quilt may be rolled on the end rail 11 with the side rails 10 as a track and the two legs may at the same time be 5 shifted inwardly to shorten the entire frame. The bolts 14 and 15, and particularly the latter, are rotatable in the apertures as best shown in Figures 3 and 4. During the quilting operation and while the bolts 15 are in the clamping relation 10 with the posts, their projecting end portions are downturned to engage the end rails but when the end rails are to be rolled, the bolts are not only released from clamping position but they are turned into the Figure 3 position to leave the end 15 rails free for rolling movement on the side rails as tracks.

The use of my quilting frame stand obviates the need for any improvised support such as chair backs which are repeatedly needed for other purposes before the work of quilting is completed. In such cases the frame and quilt must be carefully deposited on a bed until the chairs are again available after which the frame and quilt must again be carefully shifted. The shifting is difficult 25 because the old style quilting frame clamps do not maintain the frame sufficiently rigid as the clamps are too fragile to sustain much pressure. I dispense entirely with the prior clamps which are so fragile that they are apt to break when 30 they fall to the floor and I use instead the clamps 16 and 15 which are secured to the legs or posts 12 to make the quilting frame and its support a unitary and very rigid structure. When no quilting is being done, the four posts are folded and 35 they then occupy but very little more space with the quilting frame than the quilting frame alone would occupy.

Having thus described my invention in such full, clear and exact terms that its construction 40 and utility will be readily understood by others skilled in the art to which it pertains, what I claim as new and desire to secure by Letters Patent of the United States is:

1. A quilting frame and a support therefor, said quilting frame including a pair of side and a pair

of end rails arranged in contiguity with said side rails, legs at the corners of said quilting frame, bolts passing through said legs in parallelism with said end rails and having upwardly projecting arms at the inner extremities thereof for both supporting said side rails and for clamping said side rails against said legs, and other bolts for engaging said end rails, said end rail engaging bolts being in parallelism with said side rails and being positioned above said side rails at a distance substantially equal to the vertical thickness of said end rails and having downturned end portions for clamping said end rails against said legs, the arrangement being such that the release of said last named bolts will leave said end rails free to be 10 rolled on said side rails as a track. 15

2. A quilting frame consisting of a pair of side rails and a pair of end rails arranged in rectangular form, a stand for supporting said quilting frame, said stand comprising four posts at the corners of said frame, said posts and said end and side rails being all rectangular in cross section whereby said posts and rails may be firmly seated against each other, said posts being each provided with a plurality of pairs of vertically spaced apart apertures, the lower of the apertures of each pair of apertures being transverse of the quilting frame and adapted for the reception of a projecting L-shaped bolt for supporting an end of one of said side rails whereby said side rail may be clamped to the post, the upper of the apertures of the pair of apertures being positioned longitudinally of the quilting frame and vertically spaced from the lower of the pair of apertures a vertical distance substantially equal to the combined vertical thickness of an end rail and a side rail, an end rail resting on the side rail and adjacent one of said posts, a bolt passing through the second named aperture and adapted to overlie the end rail and having first a downturned portion for engaging the inner side of the end rail and then an in-turned portion for engaging the lower corner edge of the end rail. 20 25 30 35 40
